UNITED STATES PATENT OFFICE.

HYMAN BLUM, OF PITTSBURGH, PENNSYLVANIA.

CELLAR-DOOR HINGE.

Application filed April 10, 1925. Serial No. 22,237.

The present invention relates to cellar doors, and has for its object the provision of a door which has the following named characteristics, to wit; the hinges used are so constructed that water cannot get into the working parts of the said hinges; ice which may form within the hinge boxes can be readily broken up by the action of certain features of the device which will be described as the specification proceeds; means of properly and sufficiently anchoring the hinge boxes in the concrete back wall in which same are set, is provided; and means is also provided for thoroughly draining the hinge-boxes, so that water cannot ordinarily lodge in them. These and other features of the present invention will be brought out hereinafter.

In the accompanying drawings forming part of this specification I have illustrated the invention in the most desirable form I have so far devised for the purpose in hand.

Figure 1 of the drawings is a plan view of a portion of a cellar door showing one of the hinges and hinge-boxes used.

Figure 2 is a vertical section on line 2—2 of Figure 1.

Figure 3 is a front elevation of Figure 1, taken from the right thereof.

Figure 4 is a vertical section on line 4—4 of Figure 1.

Figure 5 is a diagrammatic plan view of a cellar door showing the hinges in position on the door.

By numeral 1 I have indicated a hinge which is under the door-plate or sheathing 2 forming the cellar door. 3 is a metal box which is embedded in concrete 4, and said box is provided with the anchor flange 5 for the purpose of securely anchoring the hinge-box against displacement. The hinge 1 is pivoted by the two ears or pintles 6, 7 which are in engagement with complementary sockets in the sidewalls of the hinge-box. The pintles 6 and 7 have preferably enlargements 26, 26 formed on their ends which serve to retain them in the side walls of the hinge-box as shown.

The hinge member 1, is provided with a pair of inner bossed enlargements 36, 36 which form bearing points, which bear against the under face of the angle-iron cap 8, and take the "wear" at these points, and said hinge member 1 is cut away at 37, both of which features insure smooth movement

of revolution, when the hinge member 1, is revolved on its pintles.

An angle-iron 8 covers the box and the pintles 6, 7, and said angle has a depending leg 9, which is cut away at 10, 10 to permit the hinge members to operate in the hinge-box 3. The peculiar or special shape of the hinge member at points 11, 12, permits the door 2 to be raised as shown in Figure 4 upon the pintles 6 and 7, without interfering with the corner 13 of the angle-iron 8. It is seen that the hinge 1 can be inserted by its two ear pintles 6, and 7 in its bearings 14, 14 before the cap angle 8 is in position, i. e. laid in its bearings from the top downward as seen in Figures 1 and 2 of the drawings, since said bearings are open at their top at 15, 15. This arrangement of parts permits of a ready assemblage of the hinge 1 in the hinge-box 3.

It will be noted that the side walls of the hinge-box 3 are extended at 16, 16 to provide sufficient thickness for the bearings 14, 14, and that the interior of the hinge-box has a sloping cavity 17, so that any moisture which may get into the box will naturally drain away. Two screws 19, 20 on each side of the hinge secure the cap angle 8 in position, and engage suitable extensions 27, 27 formed on the side-walls 21, 21 of the hinge-box. In addition to the anchor rib 5, it will be noted that the hinge 1 has the following feature which is a very advantageous one for breaking up any ice which may have formed in the interior of the hinge-box 3, i. e. the sharp ridged "cutters" 23, 24, 25 formed on the rear portion of the hinge 1, and clearly shown in the drawings. It is evident that when the door plate 2 is raised that the said cutters 23, 24, 25 will at once crush any ice within the hinge-box 3. While I have described but one hinge, it is seen from the Figure 5, that two hinges are usually required with accompanying hinge-boxes for each cellar door, and that the angle-iron cap 8 may be continuous from 28, to 29 of said Figure 5 if desired.

Attention is directed to other features as follows. The top plate 2 extends over the angle cap 8 at 30, which prevents water getting into the hinge 1, and the hinge-box 3, and the angle takes the load on the door plate, which relieves the hinge member 1 from transferring said load to the pintles 6, and 7.

It will be also noted that while the angle cap 8 is cut away at 10, there yet remains a portion 31 of the downstanding leg of same, which is sufficient to give stiffness and strength to the angle 8, between points 32, and 33 of Figure 3.

The curved top 34 of the rear wall 35 of the hinge-box is arranged to deflect any water which may come downward, from the 10 interior of the box 3, which when it freezes hinders the operation of the hinge.

From the above it is seen that I have provided a very efficient cellar door having the features above described, and which is at 15 the same time a practical device for the purpose intended.

I claim:

1. In a cellar door, a hinge-box having an anchor flange and an inclined bottom, a 20 hinge member revolvably mounted in the walls of the hinge-box, a plurality of transverse ice-cutters formed on the rear and downwardly extending portion of the hinge member, for removing ice from the rear side 25 and bottom of the hinge-box when the hinge member is revolved on its pintles.
2. In a cellar door, a hinge-box, a hinge member having a number of transverse ice-cutters formed on its rear and downwardly 30 projecting portion, adapted to cut away ice from the rear side wall and bottom of the hinge-box when the hinge member is revolved on its axis.

3. In a cellar door, a hinge-box, a hinge member revolvably mounted in the hinge-box, a plurality of ice-cutters, formed on the rear and downwardly projecting portion of the hinge-member, an angle-iron cap adapted to completely enclose the top and front side of the hinge-box, and having a 35 cut-away portion formed therein to permit the reciprocation of the hinge member, and ice-cutters therethrough.

4. In a cellar door, a hinge-box having a pair of outwardly extended side walls formed thereon, an angle-iron cap enclosing the top and front side of the hinge-box, a hinge-member having a pair of pintles mounted in the walls of the hinge-box, an outer enlarged collar on each pintle adapted 40 to engage the outwardly extended side wall of the hinge-box and the under side of the angle-iron cap, a pair of inner bossed enlargements formed on the pintles of the hinge member, each adapted to engage the inner side wall of the hinge-box and the under side of the angle-iron cap, and a number of transverse ice-cutters formed on the rear and downwardly extending portion of the hinge member for clearing away ice 45 from the interior of the hinge-box when the hinge member is revolved on its pintles.

In testimony whereof I affix my signature.

HYMAN BLUM.
